(57) **CLAIM**

The ornamental design for a display screen with graphical user interface, as shown and described.

DESCRIPTION

FIG. 1 is a front view of a display screen with a first image in a sequence of images of a graphical user interface; FIG. 2 is a front view of the display screen with a second image in the sequence of images of the graphical user interface;

FIG. 3 is a front view of the display screen with a third image in the sequence of images of the graphical user interface; FIG. 4 is a front view of the display screen with a fourth image in the sequence of images of the graphical user interface;

FIG. 5 is a front view of the display screen with a fifth image in the sequence of images of the graphical user interface; FIG. 6 is a front view of the display screen with a sixth image in the sequence of images of the graphical user interface; and,

FIG. 7 is a front view of the display screen with a seventh image in the sequence of images of the graphical user interface.

The dash dot broken lines show a display screen that forms no part of the claimed design.

The appearance of the graphical user interface sequentially transitions between the images as shown. The process or period in which one image transitions to another forms no part of the claimed design.

1 Claim, 7 Drawing Sheets
